US0D1063919S

(12) **United States Design Patent** (10) **Patent No.:** **US D1,063,919 S**
(45) **Date of Patent:** **** Feb. 25, 2025**

(54) **VIDEO PROCESSING APPLIANCE**

(71) Applicant: **H2VR HoldCo, Inc.**, Walnut, CA (US)

(72) Inventor: **Jeremy Hochman**, Walnut, CA (US)

(73) Assignee: **H2VR HoldCo, Inc.**, Covina, CA (US)

(**) Term: **15 Years**

(21) Appl. No.: **29/734,444**

(22) Filed: **May 12, 2020**

(51) **LOC (15) Cl.** **14-02**

(52) **U.S. Cl.**

USPC **D14/313; D14/257**

(57) **CLAIM**

The ornamental design for a video processing appliance, as shown and described.

DESCRIPTION

FIG. 1 is a perspective view of a video processing appliance showing my new design;

FIG. 2 is a front view thereof;

FIG. 3 is a rear view thereof;

FIG. 4 is a side view thereof;

FIG. 5 is a second side view thereof;

FIG. 6 is a top view thereof; and,

FIG. 7 is a bottom view thereof.

The broken lines depict portions of the video processing appliance that form no part of the claimed design.

Unshaded surfaces adjacent broken line form no part of the claimed design.

(Continued)

The shade lines in the Figures show contour and not surface ornamentation.

1 Claim, 7 Drawing Sheets
